A. H. Boyd Inventor

United States Patent Office.

AMOS H. BOYD, OF ROCKVILLE, MASSACHUSETTS.

Letters Patent No. 91,708, dated June 22, 1869.

IMPROVEMENT IN BRAIDING-ATTACHMENT FOR SEWING-MACHINES.

The Schedule referred to in these Letters Patent and making part of the same.

To all whom it may concern:

Be it known that I, AMOS H. BOYD, of Rockville, in the county of Norfolk, and State of Massachusetts, have invented certain new and useful Improvements in Sewing-Machines; and I do hereby declare the following to be a full, clear, and exact description of the same, reference being had to the accompanying drawings, making a part of this specification, and the letters of reference marked thereon, in which—

Figure 1 is an elevation of my improvement, as constructed to be applied to the sewing-machines in common use;

Figure 2 is a sectional elevation of the same; and Figure 3 is a plan of the same.

The subject-matter of my invention relates to the construction of mechanism to be attached to a sewing-machine, for the purpose of making a manufacture heretofore invented by me, called "Amosine Braid," and is so constructed that it may be attached to the sewing-machines in common use, without any material modification of the machine.

The method of making the braid, in general, consists in carrying two embroidery-threads, or cords, of any desired material, across the line of seam formed by the sewing-mechanism at each stitch, so that such threads will be interwoven with the sewing-threads, and lie upon the surface of the cloth.

This is done by means of vibrating fingers or arms, each having an eye near its point, through which the embroidery-thread is delivered, which fingers vibrate across the line of the seam at each stitch, and carry each thread alternately to either side.

My invention consists in a mode of constructing and arranging the mechanism that applies the embroidery-threads, or cords, as hereinafter described, so that such mechanism is a separate structure, and complete within itself, and may be attached to or removed from a sewing-machine, as desired, and is operated by the reciprocating motion of the mechanism that operates the needle, or some other reciprocating movement corresponding to the same, in such a manner, that at each reciprocation of the needle-mechanism, the embroidery-arms are vibrated alternately in opposite directions, and rest a sufficient length of time to enable the sewing-threads to secure the embroidery-threads to the cloth.

In the drawings—

A is a plate, upon which all the parts are arranged, as shown.

B is a slide, working vertically in guides C C, attached to the plate A.

This slide is depressed at every depression of the

needle-arm, by some part of the arm coming in contact with it, and again raised by the spring E, till it encounters the stop D.

F and G are the vibrating arms, which carry the embroidery-threads, which have their fulera at H, and, at their lower ends, eyes F' and G', through which the embroidery-threads pass and are delivered.

I is a lever, having four arms, to two of which, opposite, the vibrating arms F and G are respectively attached, by the connecting-rods F² and G², and to the other two arms are attached two pawls or latches J J, which extend upward toward the slide B.

These latches are forced inward by the springs K K, so that when the latch is not held out by other means, the inner portion of its upper end will come under the slide B.

Behind each latch is a spring-guide, L, which works in connection with a stud, L', which projects from the backside of the latch, and by means of which, when the latch rises, it is carried outward, so that its upper end will pass freely by the lower end of the slide B as it descends.

When the latch descends, the stud L' passes inside of the spring-guide, and forces it outward, until the latch arrives nearly at the lower limit of movement, when the stud passes below the spring-guide, and allows it to spring inward.

When the latch rises, the stud passes up the outside of the guide, until near the upper limit of movement, when the stud passes above the spring-guide, and is forced inward by the spring K.

By this means, the latches are alternately forced downward by the slide B, which oscillates the lever I in opposite directions, and with it the arms F and G, in a perfectly-obvious manner.

If the mechanism is designed to be attached to a sewing-machine that has a needle-bar or slide, catches attached to the same may be made a substitute for the slide B, and co-operate with the other parts in the same manner.

What I claim as my invention, and wish to secure by Letters Patent, is—

The combination of the slide B, actuated by the needle-mechanism, the spring-latches J J, the spring-guides L L, the rocking lever I, the connecting-rods F² G², with the arms F and G, constructed and operating substantially as described.

Executed, January 8, 1869.

A. H. BOYD.
